UNITED STATES PATENT OFFICE

BORIS PAWLOWITSCH ANDREIANOW, OF MOSCOW, UNION OF SOCIALIST SOVIET REPUBLICS

RAIL FASTENING DEVICE

Application filed March 6, 1930, Serial No. 433,624, and in the Union of Socialist Soviet Republics
May 17, 1929.

Due to the action of a moving vehicle, vertical vibrations are imparted to the rails of railways and in consequence of these vibrations the fastening means, as spikes and screws, are loosened. My invention has for its object to fasten the rail in such a manner that little vibrations perpendicular to the earth are permitted, while movements in a horizontal direction are prevented.

10 For this purpose, the rail is mounted on a railway chair plate by means of a dog bolt, the head of which is movable perpendicularly to the earth in a recess of the railway chair plate. This dog bolt is 15 clamped on the one hand against a vertical surface of the railway chair plate and on the other hand against one side of the flange of the rail, both by means of a clamping plate, which seizes like a hook over the flange of the rail, said rail being secured on the opposite side against transverse movement by suitable means.

The rail need no longer be firmly clamped in the hitherto usual but inefficient manner 25 against the chair plate for avoiding movements in longitudinal and transverse direction. The new fastenings of the rail are durable in a high degree and unusually efficient in operation.

30 Constructions according to the invention are illustrated by way of example in the accompanying drawings in which:-

Figure 1 is a section on line I—I of

35 Figure 2 which shows in plan a rail secured according to the invention to a chair plate which is shown in

Figure 3 with the fastening means or fitting shown in the detail views Figures 4 to 7.

40 Figure 8 is a section on line III—III of Figure 9.

Figure 9 shows in plan another form of rail fastening.

45 Figures 10 and 11 are side elevations of chair plates and

Figure 12 is a plan view of same, and

Figures 13 and 14 are detail views.

The invention consists of structural characteristics and relative arrangement of elements which will be hereinafter more fully

described and particularly pointed out in the appended claims.

The rail 1 (Figure 1) is mounted on a chair plate 2 which is secured by means of sleeper screws 3 to the sleeper. The chair plate (Figure 3) is provided at one side of the rail with a hook 4 and at the other side with a protuberance 5 and a ledge 6 which extend parallel to the rail. The protuberance 5 is provided with a hole 7 for a bolt 8 which, by means of a nut 9, presses a clamp 10 against the flange of the rail. The clamp 10 bears against the ledge 6. The hook 4 of the chair plate is undercut as shown at II—II Figure 3. At this point the chair plate is provided with an aperture 11 for the passage of a dog bolt 12 which by means of a nut 13 and of a clamping plate 14, can be clamped to the other edge of the rail flange and is therefore situated opposite the clamp 10. The dog bolt, clamp and clamping plate are illustrated in Figures 4 to 7.

The clamp 10 forces the rail 1 under the hook 4 of the chair plate. Practical experience shows that there is always a small play between the hook and the foot or flange of the rail as it is impossible to manufacture the hook and the rail so exactly as to ensure their fitting into each other without any play. The shape of the opening 11 is made to suit that of the dog 12 so that the dog engages the chair plate with its two lateral faces extending in the direction of the rail. By the action of the clamping plate 14 the rail is pressed against the clamp 10 and thus firmly secured. When vibrations are imparted to the rail by the action of the vehicle, the rail will not be moved as the dog 12 secured to its flange cannot give in the direction of the rail. Even if the clamp 10 becomes loose, the rail will not creep as long as the dog remains rigidly secured to the flange of the rail.

In the rail fastening illustrated in Figures 8-14, the rail 15 rests with one edge of its flange under the hook 16 of a chair plate constructed as shown in Figures 10-12. The chair plate is provided with a recess 18 for the reception of the dog bolt 10.

19, the axis of the bolt being horizontal. The clamp 20 can be clamped to the rail flange by means of a nut 21 and presses the rail tightly under the hook 16. The bolt 6 of the dog 19 fits without any play in the recess 18 of the chair plate. As long as it remains secured to the rail flange the rail cannot creep.

What I claim is:—

10 1. In combination, a rail having the usual foot flange, a railway chair plate having a recess on the upper surface on which said rail is mounted, a dog bolt mounted movable vertically in said recess, pressed on the one hand against a vertical surface of said recess and on the other hand against the under side of the foot flange of said rail, a clamping plate fastened by said dog bolt and seizing over one side of said rail flange, 15 and suitable means for securing the opposite side of said rail flange against movement transversely.

20 2. In combination, a rail having the usual foot flange, a railway chair plate having a recess on the upper surface on which said rail is mounted, a dog bolt mounted movable vertically in said recess, pressed on the one hand against a vertical surface of said recess and on the other hand against the 25 under side of the foot flange of said rail, a clamping plate fastened by said dog bolt and seizing over one side of said rail flange, and an undercut hook integral with said railway chair plate and receiving the opposite side of said rail flange.

30 3. In combination, a rail having the usual foot flange, a railway chair plate having a recess on the upper surface on which said rail is mounted, a dog bolt mounted movable vertically in said recess, pressed on the one hand against a vertical surface of said recess and on the other hand against the under side of the foot flange of said rail, a clamping plate fastened by said dog bolt and seizing 35 over one side of said rail flange, an undercut hook integral with said railway chair plate and seizing besides said clamping plate over said one side of the rail flange, and a clamp bearing against the other side 40 of the rail flange and fastened to the chair plate.

In testimony whereof I affix my signature.
BORIS PAWLOWITSCH ANDREIANOW.
